US0D1048006S

(12) **United States Design Patent** (10) Patent No.: **US D1,048,006 S**
(45) Date of Patent: ** Oct. 22, 2024

(54) **ELECTRONIC DEVICE**

(71) Applicant: **Cisco Technology, Inc.**, San Jose, CA (US)

(72) Inventors: **Anton Love Ingvaldson**, Oslo (NO); **Sebastian Andre Olsson**, Oslo (NO)

(73) Assignee: **Cisco Technology, Inc.**, San Jose, CA (US)

(**) Term: **15 Years**

(21) Appl. No.: **29/805,749**

(22) Filed: **Aug. 30, 2021**

(51) LOC (14) Cl. **14-02**

(52) U.S. Cl.

USPC **D14/371**; D14/126

(57) **CLAIM**

The ornamental design for an electronic device as shown and described.

DESCRIPTION

FIG. 1 is a top, front, right-side perspective view of an electronic device;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the electronic device that form no part of the claimed design.

1 Claim, 8 Drawing Sheets
